MACHINE FOR GRINDING AND FINISHING
CYLINDERS

Kirke W. Connor, Detroit, Mich., assignor to Micromatic Hone Corporation, a corporation of Michigan

Application September 12, 1935, Serial No. 40,231

3 Claims. (Cl. 51—105)

The present invention relates to the grinding and finishing of surfaces, and particularly to an improved method and machine for grinding and finishing the surfaces of cylinders.

5 It is an object of the present invention to provide an improved method and machine for grinding and finishing surfaces by which a finishing operation may be rapidly effected and an exceedingly refined surface produced.

0 It is an object of the present invention to provide a method for finishing surfaces in which, as one step, the surface to be finished is subjected to a rapidly moving abrasive and is slowly fed to the abrasive; and in which, as the second 5 step, the surface to be finished is rapidly moved across an abrasive.

It is a further object of the present invention to provide an improved finishing method as above stated, in which, in the second step, the 20 abrasive is slowly fed to the rapidly moving surface.

It is a further object of the present invention to provide an improved finishing method as above stated, particularly adapted for finishing and 25 polishing cylinders, in which, as a first step, a rapidly rotating abrasive wheel is disposed in surface engagement with a cylinder to be finished and which is slowly fed to the abrasive wheel; and in which, as a second step, the cylinder to be 30 finished is rotated rapidly in surface engagement with an abrasive wheel which is rotated relatively slowly.

It is a further object of the present invention to provide a method as last stated in which the 35 surface and the abrasive are moved in opposite directions.

It is a further object of the present invention to provide an improved finishing method as above 40 stated, in which the same abrasive is utilized in both of the above stated steps.

It is a further object of the present invention to provide an improved machine for practising the above method, and embodying driving means for rotating a cylinder and an abrasive wheel together, the abrasive wheel being rotated at a relatively high rate compared to the rotation of the cylinder in one instance, and in reverse relation in a second instance.

A further object of the present invention is to 50 provide an improved machine as above stated embodying a first train of gears selectively connectible to a driving source for rapidly rotating an abrasive wheel and slowly rotating a cylinder, and a second train of gears also selectively connectible to a source of power for rapidly rotating

a cylinder and for relatively slowly rotating an abrasive wheel.

With the above and other objects in view which will become apparent in the following description and in the appended claims, a preferred machine for practising the present invention is shown in the accompanying drawing, throughout the several views of which corresponding reference characters designate corresponding parts, and in which:

Figure 1 is a top plan view of the machine;

Figure 2 is a view in side elevation of the structure shown in Figure 1;

Figure 3 is a diagrammatic view of one of the gear trains taken along the line 3—3 of Figure 1; and

Figure 4 is a diagrammatic view of the second gear train, taken along the line 4—4 of Figure 1.

In the illustrated embodiment, the improved method and machine for grinding and finishing surfaces are applied to the finishing of cylinders. A cylinder to be finished and an abrasive wheel are rotatably supported in surface engagement, and, as illustrated, a common driving source is provided for both the wheel and the cylinder. During one step of the finishing operation, the abrasive wheel is rotated at a relatively high speed, and the cylinder being finished is rotated at a relatively low speed. This part of the finishing operation is in accordance with usual practice, and it will be understood that the rotation of the cylinder is for the purpose of gradually feeding the surface thereof to the abrasive wheel. Preferably, the abrasive wheel and the cylinders are rotated in opposite directions, so that the speeds are supplementary.

As another step of the improved method, the cylinder being finished is rotated in surface engagement with the abrasive wheel at a relatively high rate, and the abrasive wheel is rotated at a relatively low rate. In this step also the cylinder and wheel are preferably oppositely rotated. The principal finishing action is derived from the rotation of the cylinder, and the rotation of the abrasive wheel is provided principally to equalize the wear around the surface of the finishing wheel.

During the above mentioned preliminary step, in which the cylinder to be finished is rotated relatively slowly, each increment of the surface thereof is subjected, during each revolution of the cylinder, to a substantial amount of finishing action by the rapidly moving abrasive wheel. During the second step, however, the relationship is somewhat reversed, each increment of cylinder

surface being subjected, during each revolution of the cylinder, to only a minute amount of finishing action from the abrasive wheel. It has been found, in the practice of the present invention, that the first step produces a preliminary finish which has heretofore been regarded as a satisfactory final finish, and that the second step substantially further refines and perfects the finish produced by the first step.

10 It will be understood that the relative surface speeds and, consequently, the relative rates of rotation of the abrasive wheel and of the cylinder vary with different types of surfaces and different types of abrasive wheels. With certain surfaces 15 and abrasive wheels, it has been found satisfactory to operate the abrasive wheel at approximately 4000 R. P. M. and the cylinder at approximately 200 R. P. M. during the first step, and during the second step to reverse these rates and 20 operate the cylinder at approximately 4000 R. P. M. and the abrasive wheel at approximately 200 R. P. M. In certain cases, for example, the case herein illustrated, in which the diameter of the cylinder or work exceeds that of the wheel, 25 the inversion of the rates of rotation in fact increases the relative surface speeds. In other cases, the relative surface speeds may remain substantially constant, and, in certain cases, may be reduced. The characteristic relation is as recited 30 in the preceding paragraph, that is, in the second or polishing step, the surface speeds are such that each increment of work surface is subjected, per revolution, to only a minute amount of polishing action.

35 It will also be understood that the duration of the finishing operation varies considerably with the type of stone and the type of cylinder. Generally, it has been found that the first step may extend over the period customarily used for 40 the corresponding operation, and that the second step may be completed in somewhat less time.

In the form illustrated, the improved machine for practicing the above described method comprises a source of power to which either of two 45 trains of gears may selectively be clutched. The first train of gears operates the grinding wheel in one direction at a relatively high rate and the cylinder in the opposite direction at a relatively low rate. The second train of gears effects the 50 reverse operation, operating the abrasive wheel at a relatively low rate and the cylinder at a relatively high rate. Preferably and as illustrated, the wheels retain the same direction of rotation during both the first and second steps. The machine also preferably embodies readily adjustable 55 means to vary the axial spacing between the abrasive wheel and the cylinder to accommodate different sizes of finishing elements, and also take up any wear which may occur. Preferably, also, 60 these shafts which carry the abrasive wheel and the cylinder are related to at least one of the driving gears carried thereby through a free wheeling or uni-directional clutch, since in this way a single length of shafting may be used for 65 both the high and low rates of rotation of the wheel and cylinder, respectively.

Referring in more detail to the drawing, an illustrative cylinder 10 to be finished is mounted at one end of a shaft 12 for rotation thereby, and 70 an illustrative wheel 14 is correspondingly carried at one end of a shaft 16 for rotation thereby. Preferably and as illustrated, cylinder 10 and wheel 14 are removably secured to the shaft 12 and 75 16 respectively by the nuts 18 and 20. Shaft 12 is rotatably supported in bosses 22 formed in

arms 27 which are supported upon the machine frame 26. Shaft 16 is rotatably supported in bosses 24 formed at the end of arms 28, which are pivotally mounted with respect to the remaining parts of the machine, and may be secured in a desired rotative position by the adjusting screw 30. A hand wheel 32 is provided to adjust the position of screw 30 within an internally threaded boss 34 supported upon the machine, and thus adjust the relative positions of cylinder 10 and wheel 14. The upper end of screw 30 is pinned to a boss 40, which is carried by a cross bar 42 extending between the arms 28.

The main drive shaft 38 is pivotally supported upon the machine base 26 within bearing bosses 44, and acts as a support for the lower end of the previously mentioned supporting arms 27 and 28 associated with cylinder 10 and with wheel 14, respectively. Shaft 38 is also provided with an illustrative pulley 46, through which it may be 20 rotated from any desired external source of power.

Shafts 12 and 16 may be selectively geared to drive shaft 38 through either the train of gears shown in detail in Figure 4 and comprising gears 50, 52, 54, 56, 58, 60, 62 and 64; or through the 25 train of gears shown diagrammatically in Fig. 3 and comprising gears 70, 72, 74, 76, 78, 80, 82 and 84. Gears 70 and 50 are mounted on shaft 16, the drive between gear 70 and shaft 16 being direct, and the drive between gear 50 and shaft 20 16 being through a clutch designated generally as 40 90 which is of the free-wheeling or uni-directional type. Clutch 90 may be constructed in various ways and the details thereof form no part of the present invention. As illustrated, clutch 90 comprises a bored out collar 92 which surrounds shaft 16 and a spring 94, one end of which is secured to a lug 96 secured within collar 92. As will be understood, the inner end of spring 94 is free and bears against shaft 16. Rotation of gear 50 in one direction with respect to shaft 16 causes a partial unwinding of spring 94 resulting in the latter clutching shaft 16 and gear 70 together. Opposite rotation results in shaft 16 rotating freely past the end of spring 94. Gears 64 and 84 45 are correspondingly related to shaft 12 and constitute a drive for cylinder 10.

The two clusters of gears including gears 72 and 74 and gears 52 and 54, respectively, are each secured upon an intermediate shaft 100, the opposite ends of which are rotatably journaled in the previously mentioned arms 28. The corresponding pair of clusters, including gears 80 and 82 and 60 and 62, respectively, are similarly secured upon a shaft 102, the opposite ends of which are rotatably journaled in the previously mentioned arms 27.

The remaining two clusters of gears, including gears 76, 78 and 56 and 58, respectively, are freely rotatable upon the previously mentioned main drive shaft 38, and also include the clutch faces 104 and 106, respectively, which are disposed to cooperate with a conventional slidable clutch 108. Clutch 108 is splined upon the main drive shaft 38, and may be slid thereon to a position in clutching relation to face 104, as illustrated, or to a corresponding clutching position with respect to face 106, by an arm 110 pivoted at an intermediate point to a boss 112 secured to the machine base 26, and provided with a conventional bifurcated 70 inner end which carries pins 114 which enter an annular recess 116 in clutch 108.

Considering the operation as a whole and with the parts in the positions illustrated in Fig. 1, it will be understood that rotation of main drive 75

shaft 38 through pulley 46, effects a corresponding rotation of clutch 108. Clutch 108 being in engagement with face 104, the latter is correspondingly driven and as a consequence, abrasive wheel 14 is driven through the train of gears including gears 78, 76, 74, 72 and 70. Similarly, cylinder 10 is correspondingly driven, through the train of gears including gears 78, 80, 82 and 84. Due to the relation of the gears of this train, abrasive wheel 14 thus rotates at a relatively high rate, and cylinder 10 rotates at a relatively low rate. As indicated by the arrows in Figure 2 also, the directions of rotation of wheel 14 and cylinder 10 are the same but co-engaging peripheral points on the wheel and cylinder move in opposite directions, so that the speeds are cumulative. The rotation of shaft 12 also rotates gear 64 which idly drives the associated gear train, gear 60 slipping freely on shaft 16 through clutch 90.

During this stage of the operation, which, as previously mentioned, may continue for a period which varies with the material of which cylinder 10 is formed and also with the character of abrasive wheel 14, a preliminary or partial finish is given the surface of cylinder 10. As also previously mentioned, the relative rates of rotation of cylinder 10 and wheel 14 may vary, approximately 4000 R. P. M. for wheel 14 and approximately 200 R. P. M. for cylinder 10 having been found satisfactory in the practice of the present invention.

Upon completion of the preliminary finishing operation above described, arm 110 may be thrown to the opposite position, sliding clutch 108 along drive shaft 38, disengaging it from face 104 and bringing it into engagement with face 106. As will be evident, this action interrupts the driving connection for the train of gears including gear 70, and renders effective the driving connection for the train of gears including gear 60. Accordingly, because of the reverse gear ratios illustrated in Figure 4, the rate of rotation of abrasive wheel 14 is thereafter relatively low, and the rate of rotation of cylinder 10 is relatively high. During this stage, gear 70, driven by shaft 16, idly drives the associated train of gears, shaft 12 slipping freely within gear 84 through the associated clutch.

This stage of the operation applies a final finish to the surface of cylinder 10, substantially refining the finish produced during the first step, and producing an exceedingly smooth and

polished surface. As previously stated, the same abrasive wheel 14 may be used for both the first and second described states of the finishing operation, so that a complete finishing operation including both steps may be effected without interrupting the rotation of the main drive shaft 38.

Although a specific embodiment of the present invention has been shown and described, it will be evident that various changes may be made in the mode of practising the improved method, and that various changes in the form, number and arrangement of parts of the improved machine may be made, within the spirit and scope of the present invention.

What is claimed is:

1. A machine for running a cylinder in engagement with an abrasive wheel to finish the former comprising means for rotatably supporting said cylinder, means for rotatably supporting said wheel, a common source of power for said cylinder and wheel, a first train of gears interconnecting said cylinder and wheel, a second train of gears interconnecting said cylinder and wheel, and means for selectively connecting said trains of gears to said source of power.

2. A machine for running a cylinder in engagement with an abrasive wheel to finish the former comprising means for rotatably supporting said cylinder, means for rotatably supporting said wheel, a source of power common to said cylinder and said wheel, means including a first train of gears and a one-way clutch interconnecting said cylinder and said wheel, means including an additional train of gears and a one-way clutch for interconnecting said cylinder and said wheel, and means for selectively connecting said trains of gears to said source of power.

3. A machine for running a cylinder in engagement with an abrasive wheel to effect a finishing operation of the former, comprising means for rotatably supporting said cylinder, means for rotatably supporting said wheel, a drive shaft common to said wheel and cylinder, means connecting said cylinder and wheel to said shaft so that said shaft drives said wheel at a relatively high first rate and drives said cylinder at a relatively low second rate, and means for altering said connections so that said shaft drives said cylinder at a rate higher than said second rate and drives said wheel at a rate lower than said first rate.
